LENS FINISHING MACHINE

Kenneth C. Burroughs, Plainville, Mass., assignor
to Burroughs Optomat, Inc., New York, N. Y., a
corporation of Massachusetts

Application December 5, 1950, Serial No. 199,337

3 Claims. (Cl. 51—58)

1

This invention relates to lens finishing and particularly to a machine for carrying out the polishing operations after the lens has had the desired curvature generated thereon.

In the manufacture of glass lenses for optical uses, such as in spectacles, the lenses may be formed to the proper curvature in various manners. After a lens has been ground, the final operation usually comprises a polishing operation wherein rouge cerium oxide or other abrasive is employed in conjunction with a suitable tool brought into contact with the rotating blank. It is desirable in many instances to oscillate the axis of the tool relative to a rotating lens blank rotating on a fixed axis. Accuracy is of prime importance in quantity production manufacture of lenses so that all elements of the machines used must be constructed so as to eliminate errors, particularly those which might be caused by wear of the parts. It also is desirable to be able to adjust the various parts of the machines with ease and accuracy.

One of the objects of this invention is to provide an improved oscillating mechanism and arrangement for a lens polishing or finishing machine.

In one aspect of the invention, a plurality of polishing tool spindles are employed in each unit or frame, preferably four. Of course, there may be more or less arranged on a frame as desired. The unit frame and operating parts for the work spindles, for example, may be similar to those described generally in applicant's copending application Serial No. 199,335 filed December 5, 1950.

Each of the work blank spindles may be driven and may be axially movable into contact with the polishing tool. Preferably, a work blank spindle is raised by means of mechanism having a yieldable connection so that each spindle can be brought to a fixed stop regardless of over travel of the raising mechanism. Thus, by such an arrangement, each work spindle can be adjusted to move to the correct position relative to its tool. Each polishing tool is held by a rotatable tool spindle and air or spring pressure employed to urge the spindle and tool toward a blank to provide a desired surface pressure on the lens to be polished. The spring pressure arrangement shown in applicant's copending application Serial No. 199,336 filed December 5, 1950, preferably is used. The tool itself may be a shaped disc universally mounted on the rotatable tool spindle. Preferably, the tool is smaller in diameter than the lens.

Each tool spindle head is carried on an oscillatable frame mounted on a shaft means carried by the main machine frame. A connecting link is arranged to be carried by spaced arm means, said arm means being pivotally carried by said

5 frame shafts or serving as a bearing for one end of said shaft means. The arm means are oscillatable relative to their shaft means and are not connected therewith. Suitable adjustable connections are provided between each of the tool head frame means and the link means.

As a result of the construction and arrangement of the invention, the relative oscillating movement between the arm and the shaft will be 10 small and wear will be minimized. Furthermore, the arrangement can be easily adjusted.

These and other objects, advantages, and features of the invention will become apparent from the following description and drawings which are 15 merely exemplary.

In the drawings:

Figure 1 is a fragmentary rear view of the upper part of a machine employing the present invention.

Figure 2 is a reduced fragmentary schematic top view of the arrangement of Figure 1.

Figure 3 is an enlarged fragmentary view of one of the tools and a work blank.

Figure 4 is an enlarged fragmentary view partially in section of a tool head frame.

Figure 5 is a fragmentary enlarged view of one form of spring pressure arrangement.

The invention will be described in conjunction with a four-spindle machine, but it is to be understood that it may be used with a greater or lesser number of spindles, there being at least 20 two involved.

Each of the tool spindles may be mounted in a tool spindle head 10 carried by the spindle head frame 11. Each spindle frame 11 is mounted on a shaft means 12 which may extend through the frame or may merely comprise end shaft members. The front end of each shaft means 12 is carried in a suitable bearing 12¹ at the front end 25 of the machine frame. The rear journals or bearings for the shafts 12 are located at the rear of the machine frame 11.

Link carrying arms 15, 15¹ are located at spaced positions relative to each other, the hubs 14 of arms 15, 15¹ being carried on the ends of appropriate shaft means 12. Thus, the hubs 14 of the arms 15, 15¹ are oscillatable relative to shaft means 12, shaft means 12 being oscillatable in its bearing 16. It can be seen that the relative movement between hub 14 and shaft means 12 will be small, inasmuch as they will be moving in the same direction throughout almost all of their movement.

Link bar 18 is connected to the various tool head frames by means of slots 19 therein receiving rollers 20. Rollers 20 are attached to the link 18 by bolts or stud members 21, said bolts being adjustable longitudinally of link 18 in link slots 22.

A bracket 23 is fastened at 24 to link 18 and is

pivotedly attached to arm 15 by bolt 25. Bracket 26 is fastened to the link 18 at 27 and to arm 15' by bolt 28. The extension 29 is connected at 30 to the rod 31, said rod being adjustably connected to the eccentric 32 at 33. Motor 34 is employed to drive the eccentric, operation of motor 34 serving to reciprocate link 18, which in turn will oscillate the various tool heads, link 18 being carried by arms 15 and 15'.

The spindle head 10 (Figure 3) can carry a rotatable plate or support 35 to which is attached tool 36, said tool 36 being mounted thereon by means of a universal link 37 so that the tool can move universally in following the lens surface.

Lens blank 38 is carried by a blank holder 39, which in turn is held by the rotatable and axially reciprocable work spindle 40. The blank holder has a tapered aperture therein fitting a tapered end of the work spindle so as to position the work holders predeterminedly thereon.

The work spindle is raised to a fixed stop which is adjusted so that the lens blank is in contact with tool 36. The tool 36 preferably is urged downwardly by a spring (not shown) against the work. The spring force mechanism may be similar to that illustrated in copending application Serial No. 199,336. As the work spindle is rotated, the tool will rotate and will be oscillated. It is possible to positively drive the tool by mounting an appropriate motor on the frame 11.

One form of spring mechanism is seen in Figure 5 wherein tool spindle holder 126 can be mounted on an arm 110 (Fig. 3), tool spindle holder 135 having a spring 136 located between the upper surface of member 133 and the plate 135' of the holder 135. Spring arrangement 137 can be provided for applying spring pressure downwardly and thereby furnishing pressure on the tool relative to the lens surface when in contact therewith during the finishing. Spring 138 is located in holder body 139, the spring urging member 140 outwardly, member 140 having a ball element 141 through which force is transmitted to spindle 135. Spindle 135 is rotatable relative to spring holder 139 ball element 141 permitting such movement.

Plug 142 is screw-threadedly engaged in holder 139, said plug providing an upper abutment for spring 138. The plug 142 also can have attached thereto a leaf latch spring 143, said latch spring having an aperture 144 therein through which stem 145 connected with member 140 passes.

Air operated release latch 146 is located in a suitable aperture in plug 142, the latch having an aperture 147 therein reciprocally receiving the upper end of plunger 145 where pressure may be introduced at appropriate times through opening 149. As the latch release 146 is moved downwardly, it will contact leaf latch 143 and straighten it out relative to stem 145, thus releasing its grip upon the stem so as to permit spring 138 to act against member 140 and thus urge the tool toward the work. The tool 36 of Fig. 3 can be suitably fastened to the end A of the spindle of Figure 5.

It is to be understood that details of construction can be varied without departing from the spirit of the invention except as defined in the appended claims.

What is claimed:

1. In a lens finishing machine or the like having a plurality of rotatable finishing tool heads and spindles and a plurality of work spindles

cooperable therewith for carrying work in contact with said tools, the combination including a main supporting means, a plurality of oscillatable frame means holding each of said tool heads, finishing tools rotatably mounted on each of said tool heads, a plurality of shaft means mounted on said machine main supporting means and rotatably carrying each of said oscillatable frame means, a reciprocable link means adjustably connected to at least some of said frame means for oscillating the same, driving means connected to said link means for reciprocating the same, oscillatable link carrying arm means pivotally mounted on at least two of said shaft means, and connections between each of said arm means and said link means supporting said link, said oscillatable arm means being relatively rotatable relative to the shaft means upon which it is mounted for oscillating each tool 20 relative to its work piece.

2. In a lens finishing machine or the like having a plurality of finishing tool heads with rotatable tools spindles thereon and a plurality of work spindles cooperable therewith, the combination 25 including a main machine support means, on oscillatable frame means for each of said tool heads and upon which the head is mounted, a plurality of pivoted shaft means mounted on said main machine support means carrying each 30 of said oscillatable frame means, reciprocable link means, adjustable means connecting said link means to each of said oscillatable frame means, driving means connected to said link means for reciprocating the same, link carrying oscillatable arm means pivotally mounted on each of said shaft means, and connections between each of said arm means and said link means carrying said link means, said arm means being relatively rotatable relative to the shaft 35 means upon which it is mounted.

3. In a lens finishing machine having a plurality of finishing tool heads and spindles with rotatable tools on each spindle and a plurality of work spindles cooperable therewith and movable so as to bring the tool and work into contact, the combination including a main machine frame, oscillatable frame means for each of said tool heads, said tools being mounted upon said tool heads, a plurality of shaft means mounted 45 on said machine pivotally carrying each of said oscillatable frame means, reciprocable link means, adjustable means connecting said link means to each of said oscillatable frame means including a roller and slot connection therebetween, driving means connected to said link means for reciprocating the same, oscillatable link carrying arm means pivotally mounted on two of said shaft means, and connections between said link carrying arm means and said 50 link means supporting said link means, said arm means being rotatable relative to each of the shaft means supporting the same.

KENNETH C. BURROUGHS.
